UNITED STATES PATENT OFFICE.

CHARLES BURNHAM, OF LOS ANGELES, CALIFORNIA, ASSIGNOR TO BURNHAM BASKET COMPANY, A CORPORATION OF CALIFORNIA.

BOX-MAKING MACHINE.

1,119,342.

Specification of Letters Patent.

Patented Dec. 1, 1914.

Original application filed December 26, 1908, Serial No. 469,250. Divided and this application filed November 29, 1912. Serial No. 734,154.

To all whom it may concern:

Be it known that I, CHARLES BURNHAM, a citizen of the United States, and a resident of Los Angeles, county of Los Angeles, and 5 State of California, have invented certain new and useful Improvements in Box-Making Machines, of which the following is a full, clear, and exact description.

This invention relates more particularly 10 to feed mechanism for the body material of basket or box machinery in which boxes or like containers for berries or other fruit are made from thin sheet material and is a division of my pending application, Ser. No. 15 469,250, filed Dec. 26, 1908.

The primary object of the invention is to provide simple and efficient mechanism whereby a large number of shocks may be held in one or more holders or magazines 20 and the shocks automatically fed in position to be removed and automatically conveyed to box-forming means.

Other objects of the invention are to provide simple and efficient means for detachably holding the shocks holding magazines in 25 order that the shocks may be readily replaced; to provide simple means for automatically feeding the shocks and for automatically stopping the feed in case the shocks 30 should be fed in the magazines too rapidly; and to provide simple and efficient means whereby the shocks or body material may be automatically assembled from a plurality of magazines and the shocks arranged cross-wise and automatically discharged into a 35 carrier to be fed to the box-making mechanism.

A further object of the invention is to 40 provide simple and efficient means forming a part of the box-forming means which is adapted to receive the body material cross-wise and to convey the same to the remainder 45 of the box-forming means.

With these and other objects in view, the 45 invention will be hereinafter more particularly described with reference to the accompanying drawings, which form a part of this specification, and will then be pointed out in the claims at the end of the description.

In the drawings, Figure 1 is a front perspective taken from the operator's side of

the machine and looking in the direction indicated by arrows 1, Figs. 3 and 4. Fig. 2 is a rear perspective looking in the direction indicated by arrows 2, Figs. 3 and 4. Fig. 3 is a perspective of the shock end of the machine as indicated by arrows 3, Figs. 1, 2 and 4, the magazines being omitted. Fig. 4 is a top plan perspective, indicated by arrows 4, Figs. 1, 2 and 3. Fig. 5 is a horizontal fragmentary sectional detail on line V—V, Fig. 16. Fig. 6 is a view similar to Fig. 5 and showing the parts in a different position. Fig. 7 is a horizontal section 65 upon an enlarged scale taken upon an irregular line substantially as indicated by VII—VIII, Figs. 1, 2, and 10, drawn for the purpose of showing a plan of the magazine for holding the stock of body-material, the 70 dies for receiving the body-material, and the mechanism for placing the body-material in the dies. Fig. 8 is a vertical sectional detail on line VIII—VIII of Fig. 7. Fig. 9 is a horizontal sectional detail on 75 line IX—IX of Fig. 8. Fig. 10 is a vertical section upon an irregular line substantially as indicated by line X—X of Figs. 4 and 7, parts being broken away to economize space. Fig. 11 is a horizontal section 80 through one of the magazines taken on lines XI—XI of Figs. 12 and 14. Fig. 12 is a vertical section taken on line XII—XII of Figs. 4, 11, 13 and 14. Fig. 13 is a fragmentary section taken on lines XIII—XIII 85 of Figs. 7 and 12. Fig. 14 is a vertical section cross-wise of Fig. 12 and taken on lines XIV—XIV of Figs. 4, 7, 11 and 12. Fig. 15 is a fragmentary horizontal section taken on lines XIV—XIV of Figs. 12, 13 90 and 14, and Fig. 16 is a fragmentary side elevation as indicated by the arrow 16 in Fig. 12.

While the invention set forth herein more particularly refers to feed mechanism which 95 as a whole or in part may be used for various purposes, it is intended that such mechanism is primarily adapted for use in connection with box-making machinery adapted to form boxes of a special kind. These boxes 100 are adapted more particularly for the use in handling fruit and the like, and such boxes are usually rectangular in form and made from two shocks or pieces of body

material placed cross-wise. The shooks thus arranged are formed into a box body and the upper edges of the box body held and bound together by a metal binding applied to the box body. The binding metal as placed in the machine is in the form of a narrow strip and is fed into the machine at one end and is folded lengthwise, tilted and cut transversely to the proper size according to the size of the box being made. The folded strip is then bent transversely about an anvil or former and held supported thereby about a part of the box-forming mechanism. The shooks are automatically fed upwardly in a plurality of magazines and the shooks are removed by automatic mechanism and delivered so as to be held cross-wise in a suitable carrier which in this particular mechanism forms a part of the box-forming means and co-operates with the rest of the mechanism to form the box body. The box body after being formed has a metal binding clenched thereon and the completed box is held in the carrier and by it conveyed away from the box forming means in position to be discharged from the machine. The discharging mechanism forces the completed boxes in succession from the carrier and into a discharging chute in which the boxes are stacked.

As the means for bending and forming the binding metal is not claimed in this application, no attempt will be made to describe these parts specifically, such parts for forming the binding being referred to in a general way only and simply to indicate the general operation of the machine.

The metal binding as a strip 1 is held in the form of a reel and is advanced or carried from the reel by the mechanism A and the outer face of the binding metal is finished by the mechanism B. The binding metal is fed intermittently by the mechanism C and is centered lengthwise on the machine by the mechanism D. This centering mechanism D co-operates with the mechanism E which folds the strip lengthwise substantially V-shaped in cross-section after which the folded strip is tilted so as to present one of the sides in a substantially vertical plane by the mechanism F. The strip is then cut transversely by the mechanism G and one end of the cut strip is reformed by the mechanism H so that when the binding metal is bent transversely and rectangularly the ends of the binding metal may be made to overlap and lie substantially flush. The binding metal as thus formed is guided by the mechanism I to suitable bending mechanism which is adapted to bend the binding metal transversely into substantially rectangular form about a clenching anvil or former J. The mechanism for bending the binding metal around the anvil is indicated by K and the mechanism L is for causing the

ends of the binding metal to overlap as it is formed about the anvil, the said binding being held upon the anvil by the mechanism M. These several mechanisms are described in detail in my application hereinbefore referred to of which this is a division, and said mechanism may be of any suitable or preferred construction.

The mechanism N in the form of magazines for holding the stock of body material, is shown in Figs. 1, 2, 4, 7, and 10 to 16, and is omitted from Fig. 3. There are two magazines each comprising a base 302, a rear wall 303, and walls 304, 305 extending forward from the rear wall and forming a vertical trough-like member or chute 306 to receive the body-material 307, the three walls of the magazine being preferably of boards framed together by the lower brace 308 and the upper brace 309, said braces being in the form of angle-irons in cross-section as shown in Fig. 14, and U-shaped in plan as shown in Fig. 11. The magazine chutes as thus constructed are portable so that they may be removed from the magazine-mechanism and filled and then replaced. The screw-supporting posts 310 and 311 of each magazine extend upwardly from the center of the forward side of the base 302, the upper ends of the posts being connected by the feed-screw bearing 312. Each magazine has a feed-screw 313 which is mounted vertically with its upper end in the bearings 312, the body of the screw being arranged between the posts 310 and 311, and the point of the screw in a supporting bearing in the base 302, and there being crank-handles 313' for manually operating the screw. Arms 314 and 315 extend in opposite directions outwardly from the upper ends of the posts 310 and 311 and then backwardly to the edges of the side walls 304 and 305, and supporting pins 316 and 317 are fixed in these arms and project outwardly in alinement. The bases 302 must be rigidly secured either to the floor or to the main base of the machine, preferably the latter as shown in Fig. 5. Cleats 304' and 305' are secured horizontally to the lower ends and inner faces of the sides 304 and 305 to form a bottom for the magazine and hold the shooks when the magazine chute or member 306 is removed from the frame or when the magazine chute is being filled in its removed position. A plurality of notches are formed in the lower edges and forward ends of the brace 309 to hook over the pins 316 and 317 to secure the upper end of the magazine to the posts 310 and 311. Pins 318 and 319 project outwardly from the ends of the base 302, and teeth 320 and 321 project downwardly from the brace 308 between the pins 318 and 319 to secure the lower end of the magazine to the base so that by raising the magazine chute 306

bodily to disengage the teeth 320 and 321 from the pins 318 and 319 and disengage the brace 309 from the pins 316 and 317 the magazine chute or member 306 is disconnected from the magazine-mechanism.

Suitable mechanism as the mechanism O is provided for feeding the body-material into position to be picked from the magazines. Each magazine bottom 322 has rollers 323 to engage the front or inner faces of the posts 310 and 311, and an arm 324 through which the screw 313 passes freely extends from the bottom between the posts and carries rollers 325 to engage the back or outer sides of the posts. These rollers 323 are at the lower face of the bottom plate and the rollers 325 are in a plane considerably above the bottom plate, so that pressure downwardly upon the bottom will not cramp the rollers upon the posts as would be the case if the rollers were in the same horizontal plane so that the bottom 322 may travel freely up and down along the posts. A split nut consisting of the jaws 326 and 327 operates upon each screw 313. The jaws 326 and 327 are formed integral with the levers mounted upon pivots 328 and 329. The ends of the levers opposite the jaws serve as handles and project beyond the outer faces of the posts for manual operation, and a spring 330 is inserted between these handles to hold the jaws of the two parts of the nut in engagement with the screw. When it is desired to manually shift the bottom 322 up or down in the magazine, the handles 331 and 332 are manually grasped to compress the spring 330 and open the jaws 326 and 327 to release the jaws from the screw. The bottom at this time may be readily moved up and down to the desired position, and if the handles are released the jaws will again clutch the screw. When one of the magazine members 306 has been filled with the body-material 307 it is placed in position with the bottom 322 under the body-material. In other words, the bottom 322 is first lowered to the base 302, and then the magazine is placed in position with the body-material resting upon the bottom 322. The body material 307 may be in the form of thin wooden slabs commonly called shooks.

There are two of the magazines N set in relation to the machine, as shown in Fig. 4, and upon an enlarged scale in Fig. 7, the magazines being so located upon the floor that the shooks may be readily picked from the magazines and placed in the dies forming a part of the means to make the box form as will be presently described. The magazines are located directly upon the floor instead of upon a base so that they will be of considerable height, capable of receiving a considerable stock of the body-material. In order to distinguish one magazine

from the other, I designate in Fig. 7 the forward magazine as N and the rear magazine as N', it being understood that the magazine constructions are identical and that they are distinguished only as to location.

An operating-shaft 333 is mounted in brackets secured to the posts of the magazine N, and a similar operating shaft 334 is mounted in brackets secured to the posts of the magazine N'. A crank-arm 335 is fixed upon the shaft 333, and a similar crank-arm 336 is fixed upon the shaft 334, said crank-arms being parallel and connected by an adjustable connecting-rod 337. The shaft 334 has a crank-arm 338 fixed thereto and a slotted bolt 339 is rotatably mounted vertically through the outer end of this crank-arm. A sleeve 340 is pivotally mounted in the slot of the bolt 339 upon two set-screws 341, and the reciprocating transmission rod 342 is slidably mounted in the sleeve 340, there being set-collars 343 and 344 upon the transmission-rod 342 upon each side of the sleeve 340, so that as the rod 342 reciprocates the collars will alternately strike the ends of the sleeve, thereby operating the crank-arm 338 to rock the shaft 334, and through the crank-arms and connecting-rod 337 correspondingly rock the shaft 333. The set-collars 343 and 344 are set some distance apart so as to cause lost motion between the reciprocating transmission-rod 342 and the sleeve 340, and this lost motion may be increased or decreased by adjusting said set-collars. At 345 is a crank-arm which is fixed upon the upper end of the shaft 334. An eye-bolt 346 is rotatably mounted in the end of the crank-arm, and the feed-bar 347 is bifurcated and pivotally mounted at one end upon the head of the eye-bolt with a pin through the eye of the bolt. The other end of the feed-bar is slidably mounted in the slotted post 348, the slot in the post extending to the top of the post so as to allow the feed-bar to vibrate up and down as well as to slide longitudinally. A ratchet wheel 349 is fixed horizontally upon the upper end of the screw 313 with an annular series of ratchet teeth in its upper face, and a pawl 350 is vertically mounted through the feed-bar 347 near its center and held adjustably in position by a set-screw 351', the pointer of said pawl being normally in engagement with the teeth of the ratchet-wheel 349. A throw-off pin 351 is slidably mounted vertically in the upper end of the post 311 with a finger 352 extending into position to engage upon the upper face of the upper one of the shooks 307 as shown in Fig. 13. As the shooks are raised by the operation of the screw 313 moving the follower bottom 322 upwardly the finger 352 will be raised to raise the throw-off pin 351 to engage under the feed-bar 347 and raise the feed bar in 130

the post 348 to raise the pawl 350 out of engagement with the ratchet-wheel 349 and stop the operation of the feed-screw.

To pick the body-material from the magazines the mechanism P is provided as shown in Figs. 1, 2, 3, 4, 5, 6, 7, 8 and 9. Referring first to Figs. 1, 2, and 3, a lower arm extends diagonally from the frame, and the lower pair of bearings 353 is carried by the outer 10 end of the arm, and in a similar manner an upper arm extends from the frame and carries in its outer end the upper pair of bearings 354. The tubular picker-shafts 355 and 356 are rotatably and slidably mounted in 15 these bearings. A pair of ears 357 extends from the bearings 353, and a bell-crank lever 358 is pivotally mounted between the ears, one end of the lever 358 being horizontal and the other end of the lever being vertical. 20 Rollers 359 and 360 are mounted upon trunnions projecting horizontally from opposite sides of the free end of the horizontal member of the lever 358 between the tubular shafts 355 and 356, and sleeves are fixed 25 upon the shafts adjacent to the rollers, and segmental lugs 361 and 362 project inwardly from the shafts and ride upon the rollers so as to support the shafts. A cam is fixed upon a drum 401 and comprises two oppositely-arranged concentric cam-surfaces 363 and 364, there being retreating notches 365 and 366 between the ends of these cam-surfaces. 30 At 367 is a cam-fork which is mounted to reciprocate above the cam surfaces 363 and 364, there being a cam-roller 368 mounted on a trunnion extending downwardly from the fork to engage said cam-surfaces. The adjustable connecting-rod 369 connects the cam-fork 367 to the lower end of the 35 bell-crank lever 358 by a ball-and-socket joint, so that as the drum 401 rotates, the roller 368 riding upon the cam-surfaces 363 will elevate the tubular picker-shafts 355 and 356, and as the roller reaches the notch 365 and retreats into the notch the picker shafts 355 and 356 are lowered, and then as the roller rides upon the cam-surface 364 the shafts are again raised until the roller reaches the notch 366 where the shafts 40 are again lowered, thereby making the shafts go up and down twice during each cycle of the machine. The upper ends of the shafts 355 and 356 are in the form of elbows, and tubular arms 370 and 371 are adjustably connected to these elbows and held by jam-nuts. 45 A picker-plate 372 is rigidly secured to the outer end of the tubular arm 370. Fingers 373 and 374 are formed integral and transversely of the ends of the plate 372, there being suckers 375 extending downwardly from the plate between the fingers. In a similar manner the picker-plate 376 is rigidly connected to the outer end of the arm 371, fingers 377 being formed integral with

and transversely of the ends of the plate 65 376, and suckers 378 project downwardly from the plate between the fingers. The details of the picker-plates and suckers are shown in Figs. 8 and 9. Each picker-plate is provided with an air-chamber 379 communicating with the tubular arm, and vertical bores 380 are formed through the plate communicating with the chamber. The lower end of each bore is countersunk to receive the inverted cup-shaped rubber-suckers 375 or 378, and bolts 381 are inserted 70 upwardly through the bores 380. These bolts have heads to fit the shape of the suckers and hold the suckers in place, there being nuts upon the upper ends of the bolts 80 to adjust the tension upon the suckers, and small passages 380 lead upwardly at the centers of the bolts and then laterally into the air-chamber 379. The two picker-plates are constructed substantially alike, 85 the only difference being the point at which the plate is attached to the arm. Two segmental gears 382 and 383 are fixed upon the lower ends of the picker shafts 355 and 356, respectively, and these gears intermesh 90 so as to connect said shafts together. A crank-arm 384 extends outwardly from the gear 382, and an eye-bolt 385 is rotatably mounted vertically through the outer end of the crank-arm, and a connecting-rod 386 is 95 slidably mounted through the eye of the bolt, there being expansive coil-springs 387 and 388, one upon each side of the eye-bolt. A knuckle-joint 389 connects the reciprocating transmission rod 342 to the end of the 100 connecting-rod 386. This knuckle-joint forms a shoulder against which the spring 388 presses in opposition to the eye-bolt, a set-collar 390 being adjustably mounted upon the connecting-rod 388 to form a shoulder against which the spring 387 presses in 105 opposition to the eye-bolt.

Referring to Fig. 10, a stud-shaft 391 is mounted vertically in and extends downwardly from the frame *a*. This shaft has 110 a jam-sleeve 392 against the frame, a washer 393 against the sleeve, a head 394 against the washer, a nut 395 upon its upper end to tighten the head against the washer, and a sleeve to hold the shaft rigid. 115 A gear 396 is mounted upon the sleeve and is in mesh with the helical toothed gear 37. A driving member 397 of an intermittent gear combination is mounted upon the sleeve below the gear 396, and is adjustably 120 connected to the gear 396 by cap-screws 398 extending downwardly through slots in the gear 396 and tapped into driving member 397. The hollow can 399 having the zigzag peripheral cam-face 400 has an internal 125 flange inserted upwardly against the lower face of the driving member 397. The drum 401 has an external flange inserted upwardly

against the internal flange of the cam, and a ring 402 is inserted around the drum 401 against its external flange, the whole being held adjustably together by bolts 403 inserted upwardly through the ring and through slots in the internal flange of the cam 399 and tapped into the driving-member 397, so that by loosening the bolts the drum 401 may be rotatably adjusted and the cam 399 may be adjusted to the extent of the slots 404 in the internal flange. A crank-block 405 is dove-tailed into the lower end of the drum 401 and is held adjustably in place by set-screws 406, and a crank-pin 407 is fixed in one end of the block. One end of the connecting-rod 386 is mounted upon this crank-pin, so that as the driving-shaft 10 is operated the worm 38 will drive the helical toothed gear 37, thereby driving the gear 396 and the driving-member 397. This will rotate the drum 401 and operate the crank-pin 407 to reciprocate the connecting-rod 386 which will operate the crank-arm 384 and rock the picker-shafts 355 and 356. The rotation of the drum 401 operates the cam-fork 367 and the connecting-rod 369 to raise and lower the picker-shafts and through the picker-shafts the picker-plates 372 and 376.

Stop-arms 408 and 409 are adjustably fixed upon the lower ends of the picker-shafts 355 and 356, and adjustable contacts 410 are carried by the outer ends of the stop-arms, said contacts consisting of bolts 354 screw-threaded horizontally through the ends of the arms and held adjustably in place by jam-nuts. A retractile coil-spring 411 connects the stop-arms together, and the stop-arms are so arranged that when the connecting rod 386 moves outwardly the point of the stop-arm 408 engages the head of the stop-arm 409 and limits the rotation of the picker-shafts in that direction. When the connecting-rod moves in the other direction the point of the stop-arm 409 engages the head of the stop-arm 408 to limit the rotation of the picker-shafts in that direction, and when the stop-arms 408 and 409 strike, the springs upon the connecting-rod upon each side of the bolt 385 yield to the continued action of the connecting-rod. The spring 411 prevents backlash and rattling in the segmental gears 382 and 383. Pipe-nipples 412 and 413 are fixed in the lower ends of the tubular picker-shafts 355 and 356, and flexible pipes 414 and 415 are attached to the lower ends of these nipples. A bracket 416 is attached to the frame as shown in Fig. 7. A valve-casing-nipple 417 is placed against this bracket, and a coupling-member 418 is inserted through the bracket and tapped into the valve-casing, the head of the coupling-member engaging the opposite side of the bracket so that by screwing the coupling-member tight the valve-casing is held rigid with the bracket, as shown in Figs. 5 and 6. A pipe-nipple 419 is tapped into one member 420 of the valve-casing, and a three-way elbow 421 is screwed upon the pipe-nipple 419. A nipple 422 leads from one arm of the elbow and is connected to the flexible pipe 415, and a nipple 423 leads from the other arm of the elbow and is connected to the flexible pipe 414. The valve-casing 424 has three connections 417, 420 and 425, the pipe 426 leading from the member 425 to the suction-pump. The valve 427 is mounted vertically in the valve-casing 424 and has a straight passage 428 adapted to line up with the passage from the nipple 419 to the pipe 426, as shown in Fig. 5, and a side passage 429 is adapted to connect the nipple 419 to the coupling 418, as shown in Fig. 6. A crank-arm 430 extends laterally from the upper end of the valve 427, and a connecting rod 431 is adjustably connected to the outer end of the crank-arm, the crank pin being adjustably mounted in a slot in the crank arm. The cam-fork 432 is mounted to slide upon the drum 401 and carries a cam-roller 433 upon its upper face, and a retractile coil spring 434 connects the cam-fork to the frame to hold the fork yieldingly against the drum.

The valve-operating-cam 435 is curved to fit the drum 401, and is connected to the drum by bolts 436 inserted through flanges and tapped into the drum. The periphery of the cam 435 engages the roller 433 to reciprocate the connecting rod 431 and through the rod operates the crank-arm 430 and the valve 427 to exhaust the pressure as shown in Fig. 6, the spring 434 serving to return the valve to its normal position to connect with the suction-pump, as shown in Fig. 5. When the cam-roller 433 passes into the retreating notches 366 the picker-plates 372 and 376 have been moved by the connecting-rod 386 into position to drop into the magazines, as shown in Fig. 7, and the continued operation of the machine allowing the roller 433 to pass into the retreating notches 366 permits the picker-shafts 355 and 356 to slide downwardly by the gravity of the parts until the suckers 375 and 378 are upon the faces of the shooks. At this time the cam 435 passes the roller 433 and the spring 434 operates the valve 427 to connect with the suction-pump, thereby causing the suckers to take hold of the shooks. The continued operation of the drum 401 brings the cam-surfaces 363 into engagement with the roller 433, thereby sliding the picker-shafts upwardly to pick the shooks from the magazine. The continued operation of the drum 401 carrying the crank-pin 407 operates the connecting-

rod 386 to move the crank-arm 384 and rock the picker-shafts 355 and 356 in their bearings to carry the shooks to the dies forming a part of the box-forming means, as shown 5 in dotted lines in Fig. 7. Then the continued operation of the drum 401 causes the roller 368 to pass into the retreating-notch 365, thereby lowering the picker-plate carrying the shooks into the dies, and the 10 cam 435 engages the roller 433 to operate the valve 427 to exhaust the vacuum and release the shooks. The cam 364 will then engage the roller 368 to elevate the picker-plates from the dies, and the crank-pin 407 15 operates the connecting-rod 386 to rock the picker-shafts and return the picker-plates to the magazines, and this operation is continued at each cycle of the machine.

The mechanism Q in the form of dies for 20 forming the boxes is shown in Figs. 1, 2, 3, 4, 7 and 10. A shaft 437 is mounted vertically in the frame *a* and carries a fourway intermittent spur-gear 438 upon its lower end which is in mesh with the intermittent 25 driver 397. A die-carrier 439 is fixed upon the upper end of the shaft above the frame and rests upon the ball bearings 440. Four dies 441 are carried by the die-carrier 439, said dies being arranged in the form of a 30 square equal distances from the shaft 437 and equal distances apart, the vertical openings in the dies being of the size and shape of the proposed box. Spring-fingers 442 extend upwardly at the four sides of each 35 die to engage the ends of the shooks to centralize the shooks relative to the die and snap over the ends of the shooks and hold them in the die while the picker-plate is retreating, and similar spring-fingers 443 40 project upwardly adjacent to fingers 442 to engage the side edges of the shooks and assist in holding and registering the shooks. The shooks are laid crosswise in pairs in the carrier by the pickers, and at each operation 45 of the pickers the carrier is moved one step or a quarter-turn by the intermittent-gear-mechanism, so that the two cross shooks are by the next step carried away from the pickers or transfer means and the carrier 50 placed in position to receive other shooks.

It will be understood that many changes may be made in the construction and arrangement of the parts without departing from the character of the invention.

55 From the foregoing, it will be seen that simple and efficient means is provided whereby shooks or body material may be automatically elevated in a plurality of magazines; that simple means is provided 60 whereby the feed of the shooks or body material may be automatically controlled; and that simple means is provided for removing the shooks and feeding them cross-wise to the carrier.

Having thus described my invention, I 65 claim as new and desire to secure by Letters Patent:—

1. The combination of a plurality of magazines adapted to hold body material, independent means for each magazine 70 adapted to force the body material upwardly within the same, means for operating the magazine feeding means in unison, a carrier located at one side of said magazines and adapted to receive the body material, and 75 reciprocatory and oscillatory transfer means for removing a single piece of body material from each magazine at a time and for depositing the same at different points in the carrier to cause the body material to lie 80 crosswise.

2. The combination of a plurality of magazines adapted to hold body material, independent means for each magazine 85 adapted to force the body material upwardly within the same, means for operating the magazine feeding means in unison, an intermittently rotary carrier located at one side of said magazines and adapted to receive 90 the body material, and transfer means for removing a single piece of body material from each magazine at a time and for depositing the same at different points in the carrier to cause the body material to lie 95 crosswise.

3. The combination of two magazines angularly arranged with respect to each other and adapted to hold body material, independent means for each magazine adapted to force the body material upwardly within 100 the same, means for operating the magazine feeding means in unison, a carrier adapted to receive the body material, and reciprocatory and oscillatory transfer means for removing a single piece of body material 105 from each magazine at a time and for depositing the same in the carrier to cause the body material to lie crosswise.

4. The combination of a plurality of magazines adapted to hold body material, 110 independent means for each magazine adapted to force the body material upwardly within the same, means for operating the magazine feeding means in unison, a carrier adapted to receive the body material, 115 and reciprocatory and oscillatory transfer means for removing a single piece of body material from each magazine at a time and for depositing the same in the carrier to cause the body material to lie crosswise. 120

5. The combination of a plurality of magazines adapted to hold body material, independent means for each magazine adapted to force the body material upwardly within the same, means for operating the 125 magazine feeding means in unison, a carrier located at one side of said magazines and adapted to receive the body material, trans-

- fer means for removing a single piece of body material from each magazine at a time and for depositing the same in the carrier to cause the body material to lie crosswise, 5 and means for automatically and independently controlling the feed of each magazine.
6. The combination of a plurality of magazines adapted to hold body material, 10 independent means for each magazine adapted to force the body material upwardly within the same, means for operating the magazine feeding means in unison, a carrier located at one side of said magazines, 15 and adapted to receive the body material, reciprocatory and oscillatory transfer means for removing a single piece of body material from each magazine at a time and for depositing the same at different points in the 20 carrier to cause the body material to lie crosswise, and means for automatically and independently controlling the feed of each magazine.
7. The combination of a plurality of 25 magazines adapted to hold body material, independent means for each magazine adapted to force the body material upwardly within the same, means for operating the magazine feeding means in unison, a carrier adapted to receive the body material, transfer means for removing a single piece of 30 body material from each magazine at a time and for depositing the same in the carrier to cause the body material to lie crosswise, 35 and means for automatically and independently controlling the feed of each magazine.
8. The combination of a plurality of magazines adapted to hold body material, means for removing the body material from 40 the magazines and for holding the same to lie crosswise, a support for each magazine, means for detachably holding the magazines to the supports, a screw held in each support, a magazine bottom movable vertically 45 along each screw, manually operated means for detachably holding the magazine bottoms to the screws, means for rotating the screws of the magazines in unison, and means determined by the height of the body 50 material in the magazines for placing the screw rotating means of either magazine in an inoperative position.
9. The combination of a plurality of magazines adapted to hold body material, 55 means for removing the body material from the magazines and for holding the same to lie crosswise, a support for each magazine, means for detachably holding the magazines to the supports, a screw held in each support, a magazine bottom movable vertically 60 along each screw, means for rotating the screws of the magazine in unison, and means determined by the height of the body material in the magazines for placing the screw
- rotating means of either magazine in an in- 65 operative position.
10. The combination of a plurality of magazines adapted to hold body material, means for removing the material from the magazines and for holding the material 70 crosswise, a support for each magazine, means for detachably holding the magazines to the supports, a screw held in each support, a magazine bottom movable vertically along each screw, manually operated means 75 for detachably holding the magazine bottoms to the screws, and means for rotating the screws in unison.
11. The combination of a plurality of magazines adapted to hold body material, 80 means for removing the body material from the magazines and for holding the same crosswise, a support for each magazine, means for holding the magazines to the supports, a screw held in each support, a magazine bottom movable vertically along and engaged by each screw, manually operated 85 means for holding the magazine bottoms to the screw, means for rotating the screws in unison, and means determined by the height 90 of the body material in the magazines for placing the screw rotating means of either magazine in an inoperative position.
12. In a box-machine, the combination of a base having two upright posts, a screw 95 mounted to rotate between said posts, a bottom movable along the screw and guided by the posts, a divided nut arranged on the bottom and engaging the screw and having means whereby the nut may be released to 100 adapt the bottom to be raised or lowered, a trough-like member for the material detachably held to the posts, and transfer means for removing material from the magazine. 105
13. In a box-machine, the combination of a base having two upright posts, a screw mounted to rotate between said posts, a bottom movable by the screw and guided by the posts, means arranged on the bottom whereby said bottom may be raised or lowered independent of the screw, and a trough-like member detachably held to the posts. 110
14. In a box-machine, the combination of an upright support forming a back for a 115 magazine, a screw mounted to rotate in said support, a bottom movable along the screw and guided by the support, means whereby the bottom may be raised or lowered independent of the screw, and a trough-like 120 magazine member detachably held to the support.
15. In a box-machine, the combination of a support forming a back for a magazine, a screw mounted to rotate in said support, a 125 bottom movable along the screw and guided by the support, a divided nut arranged on the bottom and engaging the screw and hav-

- ing means whereby the nut may be released to adapt the bottom to be raised or lowered independent of the screw, and a trough-like magazine member for the body material 5 held to the support.
16. In a box-machine, the combination of a base, two uprights connected together at their upper ends, a screw mounted to rotate in the connecting portion of the uprights and in the base, a bottom movable by the screw and carrying rolls adapted to engage the uprights at the rear and front portions thereof, means whereby the bottom may be quickly raised and lowered along 10 said screw, means for automatically rotating the screw, and a trough-like part having three sides detachably held to the uprights.
17. In a box-machine, the combination of a support forming a back for a magazine, a bottom movable along said support, and a trough-like member detachably held to the support and having cleats at the lower portion thereof to initially support body material therein.
18. In a box-machine, the combination of a base, two uprights connected together at their upper ends, a screw mounted to rotate in the connecting portion of the uprights and in the base, a bottom guided by the uprights and moved by the screw, means whereby the bottom may be quickly raised and lowered along said screw, and a trough-like part having three sides detachably held to the uprights.
19. In a box-machine, the combination of a vertically arranged support, a bottom guided along said support, a screw for moving the bottom, means for rotating the screw, said bottom adapted to support body material, pins arranged at the upper and lower portion of said support, and a trough-like member having three sides and provided with hooks adapted to engage the pins to detachably hold said trough-like member to the support.
20. In a box-machine, the combination of a vertically arranged support forming a back for a magazine, a bottom guided along said support, a screw for moving the bottom, means for rotating the screw, said bottom adapted to support body material, engaging means arranged at the upper and lower portion of said support, and a trough-like member having three sides and means 55 to engage said engaging means of the support so as to be detachably held to the support.
21. In a box-machine, the combination of a support, a screw vertically arranged in 10 said support and having a ratchet, a bottom movable along said screw and adapted to be detachable therefrom to permit said bottom to be raised and lowered, said bottom being adapted to hold body material, said ratchet being located at the upper end of said screw, 65 an arm carrying a pawl adapted to engage the ratchet, a vertically movable rod having a pin projecting outwardly therefrom and adapted normally to rest upon the upper surface of the body material at one end 70 and having its other end adjacent to said arm whereby the body material may determine the position of the rod and thereby cause the pawl to engage or be disengaged from the ratchet wheel, and means 75 for moving the arm.
22. In a box-machine, the combination of a support, a screw vertically arranged in said support and having a ratchet, a bottom movable along said screw and adapted 80 to hold body material, said ratchet being located at the upper end of said screw, a horizontally reciprocating arm carrying a pawl adapted to engage the ratchet, a vertically movable rod having means adapted 85 normally to rest upon the upper surface of the body material at one end and having its other end adjacent to said arm whereby the body material may determine the position of the rod and thereby cause the pawl to engage or be disengaged from the ratchet wheel, and means for moving the arm.
23. The combination of a support forming a back for a magazine, a trough-like magazine member having three sides held 95 together and detachably held to said support, a screw held to rotate in said support, means for rotating the screw, and a bottom for the magazine having means to guide the same along the support, and means for 100 detachably holding the bottom to the screw.
24. The combination of a support forming a back for a magazine, a trough-like magazine member having a plurality of sides held together and detachably held to 105 said support, a screw held to rotate in said support, means for rotating the screw, a bottom for the magazine having means to guide the same along the support and engaged by the screw, and manually operated 110 means for detachably holding the bottom to the screw.
25. The combination of a support forming a back for a magazine, an open-ended trough-like magazine member detachably 115 held to said support, a bottom, a screw rotatably held to the support, a split nut mounted on the bottom and adapted to engage the screw to move said bottom, and means for manually operating said nut to release 120 the bottom from the screw.
26. The combination of a support having a base and upright posts forming a backing for a magazine, a trough-like magazine member detachably held to said posts, and a 125 magazine bottom movable along the posts and guided on opposite faces of said posts.
27. The combination of a carrier, two

magazines disposed in different positions and convenient to said carrier, means for transferring body material from the magazines to lie crosswise in the carrier and in 5 pairs, means for elevating the body material in the magazines, means for connecting the elevating means to work in unison, and means for automatically and independently disconnecting the elevating means by the 10 feed of the body material.

28. The combination of a carrier, two magazines disposed in different positions and convenient to said carrier, means for transferring body material from the magazines to lie crosswise in the carrier and in 15 pairs, means for elevating the body material in the magazines, and means for automatically and independently disconnecting the elevating means by the feed of the body material.

29. The combination of a carrier, means for supporting body material at two distinct points and located at one side out of the path of the carrier, means for simultaneously removing body material from both supporting means and depositing the same at different points of the carrier and causing the material from one supporting means to lie crosswise of the other, feeding means 30 for elevating the body material in the supporting means, means for connecting the elevating means to work in unison, and means controlled by the shocks for automatically stopping the feed.

30. The combination of a carrier, a plurality of magazines disposed in different positions, a carrier located at the side and away from the magazines, means for simultaneously transferring body material from the 40 magazines and depositing the same at different parts of the carrier and causing the same to lie crosswise in the carrier, means for elevating the body material in the magazines, and means for connecting the elevating 45 means to work in unison.

31. The combination of two magazines adapted to hold body material, means for removing the body material from the magazines and holding the same crosswise and in 50 pairs, a bottom movable in each magazine, a screw for moving each bottom, a shaft for each magazine, a ratchet-and-pawl mechanism for operating each screw and connected to each shaft, means for connecting the 55 shafts of both magazines to move in unison, means for oscillating one of the shafts, together with means for regulating the height of the body material in the magazines.

32. The combination of a magazine, a bottom 60 movable within the magazine and adapted to support body material, a screw for moving the bottom, a ratchet wheel held to the screw, a pivoted arm, a pawl carried by the arm and adapted to engage the

ratchet wheel, a rod independent of the arm, 65 and a pin carried by the rod and movable by the body material and adapted to move said rod to engage the arm and disengage the pawl to stop the feed when too rapid.

33. The combination of a magazine, a bottom 70 movable within the magazine and adapted to support body material, a screw for moving the bottom, a ratchet wheel held to the screw, a pivoted arm located above the magazine, a pawl carried by the arm 75 and adapted to engage the ratchet wheel, and an independent vertically movable rod having means movable by the body material and adapted to engage and lift the arm and disengage the pawl to stop the feed when 80 too rapid.

34. The combination of two magazines, a carrier, and two independent oscillating and reciprocatory devices located between the magazines and the carrier for removing 85 body material from the magazines and placing the same crosswise in said carrier.

35. The combination of a plurality of magazines, a carrier located to one side of the magazine, and movable devices located 90 at the side of and between the magazines and said carrier for removing body material from the magazines and placing the same crosswise in the carrier.

36. The combination of a plurality of 95 magazines adapted to hold body material, means for feeding the body material vertically within said magazines, means whereby the feed of each magazine may be automatically controlled, a carrier adapted to receive 100 the body material so as to lie crosswise therein, a plurality of reciprocatory and rotary heads adapted to remove the body material one at a time from the magazines and to deposit the same in the carrier, tubular 105 means connected to the heads, means for moving the tubular means vertically and for imparting a rotary movement thereto, together with means for creating suction within the tubular means.

37. The combination of a plurality of magazines adapted to hold body material, means for feeding the body material vertically within said magazines, means whereby the feed of each magazine may be automatically and independently controlled, a carrier adapted to receive the body material so as to lie crosswise therein, a plurality of heads 115 adapted to remove the body material one at a time from the magazines and to deposit the same in the carrier, tubular means connected to the heads, means for moving the tubular means vertically and for imparting a rotary movement thereto, together with means for creating suction within the tubular means.

38. The combination of a plurality of magazines adapted to hold body material,

- means for feeding the body material vertically within said magazines, means whereby the feed of each magazine may be automatically controlled, a carrier located at one side 5 of the magazines and adapted to receive the body material so as to lie crosswise therein, a plurality of heads having means adapted to remove the body material one at a time from the magazines and to deposit the same 10 in the carrier, tubular means connected to the heads, means for moving the tubular means vertically and for imparting a rotary movement thereto, together with means for creating suction within the tubular means.
- 15 39. The combination of a plurality of magazines adapted to hold body material, means for feeding the body material vertically within said magazines, a carrier located at one side of the magazines and 20 adapted to receive the body material so as to lie crosswise therein, a plurality of reciprocating and rotary heads adapted to remove the body material one at a time from the magazines and to deposit the same at 25 different places in the carrier, tubular means connected to the heads, means for moving the tubular means vertically and for imparting a rotary movement thereto, together with means for creating suction within the 30 tubular means.
40. The combination of a plurality of magazines, means for supporting and feeding body material in said magazines, a plurality of heads each provided with suction 35 devices movable toward and from said magazines and adapted to remove the body material therefrom, a vertically arranged tube connected to each head, gears connecting the two tubes together to cause the same 40 to oscillate in unison, means for reciprocating the tubes, a valve operatively connected to the tubes to adapt suction to be created therein, means for automatically actuating the valve whereby the body material may 45 be caused to be removed by the heads and to be discharged therefrom, and means receiving the body material and holding the same crosswise.
41. The combination of a plurality of 50 magazines, means for supporting and feeding body material in said magazines, a plurality of heads each provided with suction devices movable toward and from said magazines and adapted to remove the body material 55 therefrom, a vertically arranged tube connected to each head, gears connecting the two tubes together to cause the same to oscillate in unison, means for reciprocating the tubes, a valve operatively connected to the 60 tubes to adapt suction to be created therein, and means for creating suction in said heads.
42. The combination of a plurality of magazines, means for supporting and feeding body material in said magazines, a pluri- 65
- ality of heads each provided with flexible cup-shaped suction devices movable toward and from said magazines and adapted to remove the body material therefrom, tubular means connected to the heads, means for imparting a reciprocating and rotary movement to said tubular means, means for creating suction in the heads, and means receiving the body material and holding the same crosswise.
43. The combination of a plurality of 70 magazines, means for supporting and feeding body material in said magazines, a plurality of heads each provided with flexible cup-shaped suction devices movable toward and from said magazines and adapted to remove the body material therefrom, a vertically arranged tube connected to each head, gears connecting the two tubes together to cause the same to oscillate in unison, means for reciprocating the tubes, a valve operatively connected to the tubes to adapt suction to be created therein, and means for automatically actuating the valve whereby the body material may be caused to be removed by the heads and to be discharged 75 therefrom.
44. The combination of a plurality of 80 magazines for holding body material, means for feeding the body material in said magazines, a carrier adapted to receive the body material, two heads one for each magazine and each provided with flexible cup-shaped suction devices as a part thereof, two vertically movable and rotary tubes independently connected to said heads and adapted to 85 discharge the body material into said carrier, and means for creating suction in the heads.
45. The combination of a plurality of 90 magazines for holding body material, means for feeding the body material in said magazines, a carrier located at one side of the magazines and adapted to receive the body material, two heads one for each magazine and each provided with flexible cup-shaped suction devices as a part thereof, 95 vertically movable and rotary tubes independently connected to said heads and adapted to 100 discharge the body material into said carrier, and means for creating suction in the heads.
46. In a box-machine, the combination of 105 a plurality of magazines for holding body material, means for feeding the body material in said magazines, a carrier adapted to receive the body material, two heads one for each magazine and each provided with suction devices as a part thereof, two vertically 110 movable and oscillatory tubes independently connected to said heads and adapted to 115 discharge the body material into said carrier, and means for creating suction in the heads.
47. The combination of a plurality of 120 magazines, means for supporting and ele- 125

vating body material in said magazines, a rotary carrier located to one side of the magazines, and oscillatory pneumatic means located between the magazines and the carrier for picking up and placing the body material on the carrier to adapt the body material to lie crosswise.

48. The combination of means for supporting body material in different locations, 10 two heads each having a plurality of pneumatic devices and each adapted to remove one piece of the body material, means for raising and lowering the heads, and means for oscillating the heads and placing the 15 two pieces of body material from the two heads crosswise.

49. The combination of means for supporting body material, a head having an air 20 passage therethrough, tubular bolts communicating with the passage of the head, means for creating suction in the head, cup-shaped flexible devices held to the head by the bolts and adapted to engage the body material, and means for operating the head.

50. The combination of means for supporting body material, a head having an air 25 passage therethrough, tubular bolts communicating with the passage of the head, means for creating suction in the head, and devices held to the head by the bolts and adapted to engage the body material.

51. The combination of two magazines for holding body material, means for removing

the body material from the magazines at the same time, heads having means to engage 35 the body material, vertical tubular rods connecting to the heads, valve-controlled means for creating suction in the rods, means for oscillating the rods to move the heads toward each other, and cam-actuated means 40 for raising and lowering the rods.

52. The combination of means for supporting body material, heads having means to engage the body material, rods connected to the heads, means for rotating the rods in 45 unison to swing the heads toward or away from each other, a bell-crank lever for elevating and lowering the rods in unison, a cam, and a rod operated by the cam and connected to the bell-crank lever to operate the 50 latter.

53. The combination of means for supporting body material, heads having flexible cup-shaped devices to engage the body 55 material, rods connected to the heads, means for rotating the rods in unison to bring the heads toward or away from each other, and means for elevating and lowering the rods in unison.

This specification signed and witnessed 60
this 11th day of November A. D. 1912.
